UNITED STATES PATENT OFFICE.

ROBERT A. STONE, OF NORTHBORO, MASSACHUSETTS.

TRACK-SANDER.

1,123,421.

Specification of Letters Patent.

Patented Jan. 5, 1915.

Application filed April 13, 1914. Serial No. 831,679.

To all whom it may concern:

Be it known that I, ROBERT A. STONE, a citizen of the United States, residing at Northboro, in the county of Worcester and Commonwealth of Massachusetts, have invented a new and useful Improvement in Track-Sanders, of which the following, taken in connection with the accompanying drawings, is a specification.

10 The present invention relates to apparatus carried by street cars or locomotives for the purpose of delivering sand upon the track rails, and its object is to provide a simple, compact and efficient device of the character specified, by means of which the instantaneous delivery of sand upon the rails is accomplished whenever desired.

Other and further objects will appear in the following detailed description of one embodiment of my invention, reference being had to the accompanying drawings, in which—

Figure 1 is a side elevation, partly in section, showing the application of my invention to a street car. Fig. 2 is a vertical longitudinal section through the sand containing trough or box, and Fig. 3 is a section on the line 3—3 of Fig. 2.

Like reference characters indicate like parts in the several figures.

The numeral 1 indicates a sand containing box or trough, which, in the present instance, is shown disposed beneath the seat of the car. The box 1 is preferably in the form of an elongated trough closed at the ends and having its side walls downwardly converging from a point above the bottom. A removable cover 2 is adapted to fit snugly over the box, said cover being provided with a centrally disposed rectangular feed opening 3, which is closed by a door 4 hinged to said cover. Beneath said opening 3 is suspended a screen 5 having its edges bent upwardly and secured by rivets to a flange of the cover.

Within the box 1 a hood or deflector 6 extends longitudinally from end to end of the same, the said hood preferably being inverted V-shaped in cross section and projecting upwardly from the edges formed by the sides and bottom of the box as shown in Fig. 3. Between each end thereof and its central portion each side of the hood 6 is cut away as shown at 7, 7, to permit the sand, which piles up in the longitudinally extending channels between the sides of the box

and the sides of the hood, to enter the space beneath said hood. A partition 8, conforming in shape to the cross sectional contour of the hood 6, supports the same at a point midway the length of said hood, dividing the space between the hood and the bottom of the box into two chambers, hereinafter referred to as blast chambers. The partition 8 is carried by and is preferably integral with a conduit 9 supported by an annular base flange 10 resting on the bottom of the box and communicating with both of said blast chambers by means of an open upwardly extending section 11 which is diametrically divided by said partition 8. To the lower end of the conduit 9 is connected a flexible tube or pipe 12, which is led downwardly so as to have its open lower end disposed so as to deliver sand upon one of the rails on which the car moves. A pipe 13, adapted to convey compressed air or any suitable pressure medium, passes through and is supported by said partition 8, the said pipe extending through both of said blast chambers for substantially the entire length of the same. The end of pipe 13 in one of said chambers, in the present instance the right hand or forward blast chamber, has connected thereto one horizontal arm of a T-coupling 14, the depending vertical arm of which is closed at the bottom and has a plurality of lateral openings 15 on the side facing the partition 8. The other horizontal arm of the T-coupling 14 is attached to a compressed air supply pipe 16 which passes through the end wall of the box and acts as a support for the end of pipe 13. The other end of pipe 13 in the other blast chamber has connected thereto an elbow coupling 17 closed at the bottom, and provided with a series of lateral openings 18 in opposition to the openings 15 in coupling 14. The supply pipe 16 has a valve 19, at a point conveniently accessible for operation by the motorman of the car, by means of which he may cause a blast of compressed air, supplied from the usual tank, not shown, to enter the pipe 13 at such times as may be desired.

The operation of my improved device is as follows:—The box is supplied with sand through the opening 3, the sand sifting through the screen 5 and dropping by gravity onto the hood 6, and piling up in the longitudinal channels formed between the sides of the hood and the sides of the box to a sufficient

2
height to pass through the cut away portions 7; these cut away portions are spaced from the ends of the hood so as to prevent the piling up of sand around the couplings 5 14 and 17, and, furthermore, they terminate short of the space occupied by the section 11 of the conduit 9, so that sand within the said blast chambers will have no tendency to pass into said conduit unless forced into 10 the same by a blast of air. When the operator opens valve 19, a series of blasts of compressed air are made effective from the outer end of each blast chamber to force sand lying within such chambers over the 15 edge of the section 11, against the partition 8 and through the conduit 9 to the rail to be sanded. The construction of the hood facilitates the above described movement of the sand since the sand is prevented from 20 piling up in front of the air openings in a compact impenetrable mass. The blast of air thereby effects a skimming action of the sand lying in its path, and as the sand is thus forced out of the blast chambers, additional sand from the channels outside of the hood 6 moves through the cut away portions 25 7 to maintain the supply within said chambers at a substantially constant level.

I claim,
30 1. In a track sander, a sand containing box, a blast chamber within said sand containing box in communication therewith intermediate its ends, and means for directing a blast of air longitudinally of said blast chamber.

2. In a track sander, a sand containing box, a blast chamber in communication with said box, means for limiting the passage of sand from said box to said chamber, an air

nozzle within said chamber, and means for 40 preventing the access of sand to said nozzle.

3. In a track sander, a sand containing box, a hood extending longitudinally of said box above the bottom thereof, a partition dividing the space beneath said hood 45 into two blast chambers, and means for directing blasts of air toward said partition through each blast chamber.

4. In a track sander, a sand containing box, a conduit leading therefrom, a pair of 50 blast chambers within said box, each in communication with said conduit, and each having openings adapted to permit a limited amount of sand to enter from said sand box.

5. In a track sander, a sand containing 55 box, a conduit leading therefrom, a hood disposed within said box and above said conduit, said hood having its sides extended to prevent access of sand to said conduit from the sides of said box.

6. In a track sander, a sand containing box, a conduit leading from the bottom of said box and having a flange extending above said bottom, a hood extending longitudinally of said box above the bottom 60 and having lateral extensions to prevent the entrance of sand laterally to the space beneath said hood at the ends and central portion thereof, a partition extending upwardly from said conduit to divide the space beneath said hood into two blast chambers, and a pipe extending through said partition and having outlet openings adjacent the opposite ends of said blast chambers.

ROBERT A. STONE.
